Inventor:

Oliver S. Meyer

UNITED STATES PATENT OFFICE

2,188,892

DITCHER

Alvin L. Meyer, Fairfield, Mont.

Application April 7, 1939, Serial No. 266,903

4 Claims. (Cl. 37—98)

This invention relates to ditch digging devices, and more particularly to a digger embodying a triangularly shaped plow and a mobile frame including a pair of rear wheels which are adapted to straddle the ditch formed by the plow.

An object of the invention is to provide an improved ditch digging device of this type which is simple in construction, and which is so constructed that it will readily form a ditch of desired depth.

Another object of this invention is to provide a device of this type including a mobile frame and a plow supported relative to the frame, the plow being so supported at the rear thereof that it may have relative horizontal movement with respect to the frame.

Another object of this invention is to provide a ditch digging device of this type including an improved means for elevating or lowering the plow.

A further object of the invention is to provide in a ditch digging device of this type, means whereby the operator may stand on the plow between the sides thereof, the supporting means being constructed in the form of a platform which is also adapted to brace the sides of the plow.

To the foregoing objects and others which may hereinafter appear, the invention consists of the novel construction, combination and arrangement of parts as will be more specifically described and illustrated in the accompanying drawings, wherein is shown an embodiment of the invention, but it is to be understood that changes, variations and modifications may be resorted to which fall within the scope of the invention as claimed.

Figure 1 is a detail side elevational view, partly broken away, of a ditch digging device constructed according to an embodiment of this invention; and

Figure 2 is a detail top plan, partly broken away, of the device.

Referring to the drawings numeral 10 designates generally a mobile frame, comprising a pair of forwardly convergent side bars 11 and a rear connecting bar 12. The bars 11 and 12 forming the frame, are formed of angle iron and the side bars 11 have one side 13 thereof horizontal and the other side 14 vertical. The rear ends of the side bars 11 are secured to the rear bar 12 by means of fastening devices 15.

A vertically disposed front bearing 16 is positioned forwardly of the convergent ends of the side bars 11 and a substantially triangularly

shaped plate 17 is formed integral with the bearing 16 and extends between the forward convergent ends of the side bars 11. Vertical flanges 18 are formed with the plate 17 and are disposed on the inner sides of the vertical flanges 18 or sides 14 of the angle bars 11 and are secured thereto by means of fastening devices 19 in the form of bolts or the like.

A caster wheel 20 is journalled on a shaft 21 extending between a pair of rearwardly extending arms 22, which are carried by the lower end of a vertical shaft 23. The shaft 23 is journalled in the bearing 16 and a washer 24 engages about the shaft 23 on the upper end of the bearing 16. A cotter pin or locking member 25 extends through the shaft 23 above the washer 24 so as to hold the shaft 23 against endwise movement. A bracing web 26 connects the rear portion of the bearing 16 with the underside of the plate 17 so as to properly brace the bearing 16 and maintain this bearing in a vertical position.

A pair of stub shafts 27 are disposed beneath the rear frame bar 12 and are secured thereto by means of fastening devices 28. A wheel 29 is rotatably mounted on each stub shaft 27 and the wheels 29 are adapted to engage on opposite sides of the ditch formed by the plow supported from the frame 10, as will hereinafter be described. A plow, generally designated as 30, is adjustably supported from the frame 10 and comprises a pair of forwardly convergent side members or mold boards 31. The side members 31, at their forward convergent ends, are connected together by means of a plate 32 which is secured, as by fastening members 33, to the forward ends of side members 31. The plate 32 is disposed on a forwardly and downwardly inclined angle, and at its lower end the plate 32 projects downwardly below the lower edges of the side members 31, as at 34. This projecting lower end portion of the plate 32 forms a cutting or digging member which is adapted to form a relatively narrow channel at the bottom of the channel formed by the mold boards 31.

The rear ends of the mold boards 31 are connected together by means of an end member 35. The mold boards 31, adjacent the rear thereof, are each provided with a vertically disposed bar 36 which is secured to a mold board 31 on the inner side thereof, as by welding, or the like, and preferably the bars 36 and the mold boards 31 are formed with vertically spaced apart openings 37. A pivot member 38 is adapted to engage through a selected opening 37 and is also adapted to slidably engage in a horizontally disposed elongated

gated slot 39 formed in the vertical side 14 of a frame member 11 adjacent the rear thereof. The openings 37 provide a means whereby the rear portion of the plow 30 may be vertically adjusted relative to the frame 10.

A platform 40, formed of a plurality of transversely disposed boards, is disposed between the mold boards 31, and engages on the opposite ends thereof, on a supporting member 41, secured to 10 the inner face of a mold board 31. The platform 40 forms a bracing means between the mold boards 31, so as to prevent inward bending thereof, and also forms a means whereby the operator of the device may stand on the plow 30 between 15 the mold boards 31, during the operation or use of the plow.

A pair of vertically disposed elongated guide members 42 are disposed above the frame 10, and each guide member 42 is provided with a horizontal flange 43. A pair of vertically disposed supporting members or bars 44, having a horizontal extension 45 at their upper ends, are secured, as by fastening members 46, to the flanges 43 at the forward ends thereof. The supporting members 44 are secured at their lower ends to a transversely disposed forward angle bar 47, which is secured, as by fastening means 48, to the side frame members 11. The lower ends of the supporting members 44 are secured to the 25 vertical side 49 of each angle member 44, by fastening members 50.

A pair of vertically disposed rear supporting bars 51, provided with forwardly extending upper end portions 52, are secured by fastening 35 means 53 to the rear ends of the flanges 43. The lower ends of the supporting bars 51 are secured to a vertical side 54 of a transversely extending angle member 55 which is secured by fastening means 56 to the frame members 11. The lower 40 ends of the supporting bars 51 are secured by fastening members 57, to the vertical side 54.

A vertically disposed rack or toothed bar 58 is slidable between guide members 42 and the lower end of the rack bar 58 is pivotally secured at the 45 convergent ends of a pair of forwardly convergent supporting bars 59 which are secured at their divergent ends by fastening means 60 to the inner sides of the mold boards 31. As shown in Figure 1, the supporting bars 59 are disposed on 50 a forward and upward inclination, and the lower end of the rack bar 58 is pivotally secured, as at 61, to the convergent ends of the supporting bars 59. The bars 59 are provided with a forwardly extending member 62 which extends forwardly of the forward upper ends of the mold boards 31. A link 63 is secured at its forward end to the 55 bracing web 26, as at 64, and the rear end of the link 63 is secured, as at 65, to the extension 62.

60 A shaft 66 is journalled through the guide members 42 and a pinion or gear 67 is fixed to the shaft 66 between the guide members 42 and meshes with the teeth of the rack 58. A hand wheel 68 is fixed to one end of the shaft 66 and provides a means whereby the plow 30 may be 65 vertically rocked on the pivot members 38. A transversely disposed guide member 69 extends between the guide members 42 and is adapted to engage against the edge of the rack bar 58 opposite from the teeth carried thereby. The hand wheel 68 is held against rotation by means of a headed pin 70, which removably engages through the guide members 42 and is adapted to contact with one of the spokes 71 of the wheel 75 68.

A transversely extending draw bar 72 is secured at one end to the bearing 16, and is provided with a plurality of openings 73 in which draft devices are adapted to engage. A bracing bar 74 is secured, as at 75, to the upper end of the draw bar 72, and is secured, as at 76, to a side member 11 of the frame.

In the use and operation of this plow a suitable power means is adapted to be connected to the draft bar 72. The plow 30 may be lowered 10 at its forward end by removing the locking pin 70, so as to permit rotation of the wheel 68 in a direction to lower a rack bar 58. When the plow 30 has been lowered to the desired degree the wheel 68 may be locked by inserting the pin 70 15 through the guide members 42 and between a pair of spokes 71 carried by the wheel 68. Lowering of the plow 30 will cause the pivot members 38 to slide forwardly in the horizontal slots 39 of the side members 11. By providing the plow 20 30 with the plurality of spaced openings 37, the width of the ditch formed by the plow 30 can be easily and quickly adjusted. The depth of the ditch is controlled by the position of the forward end of the plow 30, as regulated by the hand 25 wheel 68. A plow constructed according to this invention will form a ditch of desired depth and width and where the width of the ditch being formed is less than the space between the rear ends of the mold boards 31, the projecting portions of the mold boards 31 will form a means to throw the loose dirt laterally of the upper edge of the ditch. By providing a flat cutting member 32 on the front end of the plow 30, the loosened dirt is not apt to drop down into the bottom of the ditch as would be the case where the forward ends of the plow mold boards are connected together in the form of a sharp point.

What I claim is:

1. A ditch digging device comprising a mobile 40 frame, a triangularly shaped plow, said frame having a pair of elongated slots adjacent the rear thereof, a pair of pivot members secured to said plow adjacent the base thereof and slidable in said slots, a link connected at one end to said frame adjacent the forward end thereof, and pivotally connected at the opposite end to the forward end of said plow, a vertically disposed rack bar, means pivotally securing the lower end of said bar to said plow adjacent the forward end thereof, guide means for said rack bar, means supporting said guide means in upwardly spaced relation to said frame, a shaft journalled through said guide means, a pinion fixed to said shaft and meshing with said rack bar, a hand wheel 45 fixed to said shaft, and means locking said wheel against rotation to thereby maintain the forward end of said plow in selected position relative to the frame.

2. A ditch digging device comprising a mobile 60 frame, a triangularly shaped plow positioned with the apex at the front end of the frame and the base at the rear of the frame, said frame having a pair of elongated horizontal slots adjacent the rear thereof, a pair of pivot members carried 65 by said plow and slidably engaging in said slot, a forwardly extending downwardly inclined link connected at its forward end with the frame and having its rear end pivotally connected with the top of the plow at the forward end of the latter, a platform carried by said plow, a vertically disposed rack bar, means pivotally securing the lower end of said bar to said plow adjacent the forward end thereof, a pair of spaced apart parallel guide members engaging on opposite sides of 70 75 75

5 said bar, a flange carried by each guide member, guide supporting means secured to and extending upwardly of said frame, means securing said flanges to said supporting means, a transverse guide extending between said guide members and
10 engageable with an edge of said bar, a shaft journaled through said guide members, a pinion fixed to said shaft between said guide members and meshing with said rack bar, a hand wheel fixed to said shaft, and means holding said wheel against rotation.
15 3. A ditch digging device comprising a mobile frame, a triangularly shaped plow positioned with the apex at the front end of the frame and the base at the rear of the frame, said frame having a pair of elongated horizontal slots adjacent the rear thereof, a pair of pivot members carried by said plow and slidably engaging in said slot, a linkage connected to the forward end of the plow, extended forwardly from the latter and having its forward end connected with the frame, a platform carried by said plow, a vertically disposed rack bar, means pivotally securing the lower end of said bar to said plow adjacent the forward end thereof, a pair of spaced apart parallel guide members engaging on opposite sides of said bar, a flange carried by each guide member, guide supporting means secured to and extending upwardly of said frame, means securing said flanges to said supporting means, a transverse guide extending between said guide members and engageable with an edge of said bar, a shaft journaled through said guide members, a pinion fixed to said shaft between said

guide members and meshing with said rack bar, a hand wheel fixed to said shaft, and a wheel locking pin removably engaging with said guide members, and engageable with said wheel to hold said wheel against rotation. 5

4. A ditch digging device comprising a frame formed of a pair of forwardly convergent bars, and a rear bar connecting the divergent ends of said bars together, a front bearing, means securing said bearing to the convergent ends of 10 said bars, a caster wheel carried by said bearing, a pair of stub shafts, means securing said stub shafts to said rear bars, a rear wheel on each stub shaft, said pair of bars each having an elongated slot adjacent the rear end thereof, a 15 triangularly shaped plow, said plow having a plurality of vertically spaced apart openings adjacent the rear thereof, pivot members engaging through selected openings of said plow and through said slots, an extension carried by the 20 front of the plow and extended up into the frame, a forwardly extending downwardly inclined link having its rear end pivotally connected to the upper end of the extension and its forward end connected with the frame, a toothed rack bar, 25 means pivotally securing an end of said rack bar to said plow adjacent the forward end thereof, guide means for said rack bar, means supporting said guide means upwardly of said frame, a shaft journaled through said guide means, a pinion 30 fixed to said shaft and meshing with said rack bar, a hand wheel fixed to said shaft, and means locking said hand wheel against rotation.

ALVIN L. MEYER.
